US00D869434S

(12) **United States Design Patent** (10) Patent No.: **US D869,434 S**
 Biao et al. (45) Date of Patent: **** Dec. 10, 2019**

(54) **SPORT EARPHONE**

(71) Applicant: **SHENZHEN GRANDSUN ELECTRONIC CO., LTD.**, Shenzhen, Guangdong (CN)

(72) Inventors: **Sheng Biao**, Shenzhen (CN); **Wu Haiquan**, Shenzhen (CN); **Zhou Shiyong**, Shenzhen (CN); **Yoshinari Okamoto**, Shenzhen (CN); **Peng Jiugao**, Shenzhen (CN); **Shi Ruiwen**, Shenzhen (CN)

(73) Assignee: **SHENZHEN GRANDSUN ELECTRONIC CO., LTD.**, Shenzhen, Guangdong (CN)

(**) Term: **15 Years**

(21) Appl. No.: **29/659,506**

(22) Filed: **Aug. 9, 2018**

(51) LOC (12) Cl. **14-01**

(52) U.S. Cl.

USPC **D14/205**

FOREIGN PATENT DOCUMENTS

EM 005609757-0001 * 8/2018

Primary Examiner — Paula Allen Greene*(74) Attorney, Agent, or Firm* — Conley Rose, P.C.; Grant Rodolph(57) **CLAIM**

The ornamental design for a sport earphone, as shown and described.

DESCRIPTION

FIG. 1 is a first perspective view of a sport earphone;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a partially enlarged view of FIG. 1.

The design which is claimed is shown in solid lines in the drawings. The broken lines shown in the drawings depict portions of the environment, and form no part of the claimed design.
